DESIGN FOR A COMBINED RESPIRATOR AND FACE SHIELD

Edward V. Karabin, Wilkinsburg, and Raymond
A. Dinkel, Mount Oliver, Pa., assignors to Mine
Safety Appliances Company, Pittsburgh, Pa.

Application December 31, 1940, Serial No. 97,743

Term of patent 14 years

To all whom it may concern:

Be it known that we, Edward V. Karabin and Raymond A. Dinkel, citizens of the United States and residents, respectively, of Wilkinsburg and Mount Oliver, in the county of Allegheny and State of Pennsylvania, have invented a new, original, and ornamental Design for a Combined Respirator and Face Shield, of which the following is a specification, reference being had to the accompanying drawing, forming a part thereof.

Fig. 1 is a top plan view of a combined respirator and face shield embodying our new design;

Fig. 2 is a front elevational view thereof with the head straps shown broken away for convenience of illustration; and

Fig. 3 is a side elevational view thereof with the head straps shown broken away for convenience of illustration.

We claim:

The ornamental design for a combined respirator and face shield, substantially as shown.

EDWARD V. KARABIN.
RAYMOND A. DINKEL.
